SAMUEL RUTTENBERG, OF BROOKLYN, NEW YORK

BALLAST RESISTANCE

Application filed March 28, 1929. Serial No. 350,584.

This invention relates to a ballast resistance and specifically to one having a wide range of resistance variation with load. It also relates to a ballast resistance utilizing the temperature resistance characteristics of iron wire in a helium atmosphere.

In the ballast resistance devices of the prior art, especially those used for the control of line voltage applied for the operation of 10 radio sets on commercial lighting circuits, a single iron wire resistance elements in hydrogen has been utilized. While a good control of line voltage to the set can be obtained with such a device, it has an inherent limitation, namely, that the initial current surge 15 through the ballast prior to its assuming an equilibrium temperature for its power consumption, is so great that it strains the electrical circuits of the devices controlled, especially the filter circuit elements such as the 20 rectifiers, condensers and cathode heaters.

In the present invention, helium is chosen as the atmosphere, because of its excellent 25 thermal conductivity, and non-explosive, inert and monatomic character, the latter characteristic aiding in obtaining a better range of resistance change with temperature than is obtained with iron alone and especially because it is not easily absorbed as is hydrogen, 30 which when absorbed, causes the iron to become crystallized and very brittle. Most of the trouble experienced with hydrogen filled ballasts has been mechanical breakage due to the iron becoming very brittle and readily 35 breaking when subjected to vibration, whereas with helium, the iron remains ductile and has a long life.

In operation of the device of my invention, when the current is initially applied, instead 40 of being directly applied to one ballast element, it is applied to two, which are connected in series. This prevents an excess rush of current and resultant straining of the load or controlled device which would otherwise occur due to the resistance being cold. 45 A thermostatic element is located near one of the resistor elements. When the iron wire resistance elements heat up, the thermostatic element, due to the heat developed, moves 50 toward a yielding or spring contact which

short circuits one of said resistor elements. The heat from the other resistor element maintains the thermostatic element in short circuit position unless there is excess heat, due to excessive line potential or other causes, 55 in which case the moving thermostatic element moves further and slides past the spring contact, again connecting the two resistor elements in series. Should the line voltage be reduced to its normal value, the 60 thermostatic element will retract and again short circuit one of the resistor elements.

A ballast tube embodying my invention is shown in the accompanying drawing.

In order to more completely describe the 65 invention, reference is made to the accompanying drawing in which R_1 and R_2 are the iron wire ballast resistance elements, enclosed in a glass tube T , having an inert atmosphere such as helium, preferably at about 70 100 mm. pressure. T_e is a thermostatic element which by effect of heat from the resistance elements R_1 and R_2 moves toward and from the yielding contact C . S is the support for the resistor elements and L_1 and L_2 75 are the supporting leads in the glass stem. The terminal prongs are designated as T_1 and T_2 .

In operation, when current is applied to the terminals, the iron wire resistor elements 80 are heated and due to the high temperature resistance coefficient of iron, there is a regulation of the current flow by an increase in the voltage drop across the resistor elements by said current. I have discovered that with 85 my new ballast tube, an increase of 10% in current will increase the voltage drop across the ballast about 200%. When the resistor elements are heated to the desired temperature, the thermostatic element T_e moves toward the contact C and short circuits resistor element R_1 . This increases the current flow in the circuit to a value corresponding to a given voltage. Should the line voltage increase beyond the control range of the single 90 resistor element R_2 , the thermostatic element T_e moves beyond the yieldable contact C and separates therefrom. This inserts R_1 in series with R_2 , thus reducing the line voltage 95 by increasing the resistance in the ballast. 100

When the line voltage again returns to its normal value, the thermostatic element moves back to engage the yielding contact and so again short circuits resistor element R₁.

When the operating switch controlling current through the ballast tube is opened, the current through the ballast resistance is cut off and stopped and the thermostatic element 10 cools down. Contact of the thermostatic element with yieldable member C is broken as element T₁ in cooling, moves to the left of member C to its normal position when the tube is not in use.

15 While I have illustrated one specific form of my invention, I mean to have the claim cover all features as common equivalents to the elements herein set forth.

I claim:

20 A ballast tube comprising resistor elements in series and automatic means including a thermostat within the tube to cut out one of said elements as the current therein increases to a certain value and to again insert said 25 element in series as the current is further increased.

In testimony whereof I affix my signature.

SAMUEL RUTTENBERG.
